UNITED STATES PATENT OFFICE.

WILLIAM C. WEEKS, OF SPOKANE, WASHINGTON.

EXCAVATING APPARATUS.

No. 882,726.

Specification of Letters Patent. Patented March 24, 1908.

Application filed May 22, 1907. Serial No. 375,167

To all whom it may concern:

Be it known that I, WILLIAM C. WEEKS, a citizen of the United States, residing at Spokane, in the county of Spokane and State of Washington, have invented certain new and useful Improvements in Excavating Apparatus, of which the following is a specification.

This invention relates to improved machinery for excavating, dredging, and transporting earth and other materials with a scoop or scraper, operated from a main power-station by means of ropes or cables, hauled so that the earth and other materials may be filled into it, transported in it, and deposited from it.

In this specification the term "forward" indicates that direction in which the scoop is drawn when it is being filled, and the term "backward" indicates the contrary direction.

The scoop is a receptacle having a closed bottom, back and sides and open front and top. Two cables are used to operate the scoop, by means of which the same is drawn to the spot where it is desired to load the same, is then loaded, drawn forward, emptied of its contents and then returned for reloading, as will be hereinafter explained. Beyond the extreme forward limit of travel of the scoop is placed, winding machinery and a pair of drums. The two cables are secured to the scoop and each operated by means of the drums of winding machinery, one adapted to draw the scoop forward and the other backward with the assistance of a pulley placed beyond the extreme backward limit of travel of the scoop, over which the cable operates.

Other particular features of mechanism will be hereinafter described and explained.

In the drawings, Figure 1 is a side elevation of the scoop in the position in which the same would be when loaded and being drawn forward to be emptied of its contents, Fig. 2 is a rear elevation of the scoop in the same position and, Fig. 3 is a side elevation of the same in the position of being loaded or of cutting into the earth.

To the front end of the scoop 16 on either side is linked the chain 23 carrying a block 10, to the shaft of which is linked the draw cable 14. Near the front end of the scoop 16 and to the sides thereof is secured a stationary bail 25, to which bail, and made stationary therewith, are secured two pulleys 11

and 12. At the rear end of the scoop 16, and made stationary therewith, is secured a pulley 13. Transversely of the scoop, near the rear end thereof and made stationary therewith is a cross-arm 22, extending across the body of the scoop and beyond the sides thereof. Linked to the shaft of the pulley 10 is the cable 15, which cable passes over the pulley 12, thence over the pulley 10, to and over the pulley 11, thence to and under the pulley 13, to and over the pulley 18 and thence to the drum of winding machinery.

Secured to the cable 15 and made stationary therewith between the pulleys 11 and 13 is a button 19 or other sufficient obstruction, adapted to come in contact with the said pulleys and not pass beyond, but to hold the cable 15 secure until a draft in the opposite direction is applied, in which case the button 19 will again be blocked at the other pulley and not permit any further passing of the cable 15 over the pulley, the significance of which will be hereinafter explained. Longitudinally arranged upon the outer side and bottom surface of the scoop, are plates 27 to serve the purpose of strengthening the scoop, the ones on the bottom serving the further purpose of runners and guides for the scoop in its passage over the surface of the earth and also to protect the body of the scoop as against wearage by preventing it from being in constant contact with the earth. It will be observed that these plates upon the bottom surface of the scoop are inclined upward on their bottom surface for a distance back from the front end thereof, inclining upward from the horizontal as they approach the forward end of the scoop being designed to assist in throwing the scoop out of the earth when the same is in a horizontal position.

In case it is not desired to have these plates on the bottom of the scoop, the bottom of the scoop itself may be bent or inclined upward as it approaches the forward end thereof, which will serve the purpose of throwing the scoop out of the earth, when the same is in a horizontal position. The plates on the side surface of the scoop serve the further purpose of steadyng the same when in a tilted position as shown in Fig. 3. These plates, it will be observed, extend forward a sufficient distance to touch or come in contact with the ground, when the scoop is tilted for loading, serving as legs or supports for the scoop while in that position, as against any inclination of the scoop to tip side-wise. All of these plates extend a dis-

tance beyond the forward end of the scoop to more thoroughly effect the objects sought. The plates on the bottom surface of the scoop are beveled at their front end in order that they may assist in penetrating the earth in the process of filling the scoop. In Fig. 3 is shown in connection with the scoop, an earth line 21.

When it is desired to operate the scoop, the winding machinery used to regulate the cable 15 is set in motion and the scoop drawn backward to the spot where it is desired to load the same. The draft on the cable 15 in drawing the scoop backward causes the block 10 to be drawn up against the bail 25 and the button 19 to be drawn against the pulley 13 as shown in Fig. 3. In order to load the scoop it is only necessary to stop the winding of the cable 15 and apply the winding machinery to draw forward the cable 14, in the mean time and during the filling of the scoop hold to proper tension the cable 15, thus applying the draft on the cable 14 at a point on the scoop near the top of the bail 25, causing the scoop 16 to tilt forward and dig into the earth 21, as shown in Fig. 3, and when the scoop is sufficiently loaded, it is only necessary to slacken the cable 15, which causes the block 10 to return to the position shown in Fig. 1, thus throwing the draft on the cable 14 to the point on the scoop 16 indicated by the link 20. This causes the scoop 16 to resume a horizontal position and the button 19 to return to its place against the pulley 11 as shown in Fig. 1, and the upwardly inclined points 17 of the plates 27 throw the scoop upwardly and out of cutting engagement with the earth 21. The loaded scoop may then be drawn forward and up an incline or otherwise, over a trap where the cross-arm 22 may engage side poles, the scoop tip forward into the trap and empty itself and then be drawn backward again by means of the cable 15 for reloading.

Having thus described my invention, what I claim as new and useful and desire to secure by Letters Patent, is:

1. In an apparatus for excavating, dredging, and transporting earth and other ma-

terials, the combination of a scoop having closed back, bottom and sides, and open front and top, with a stationary bail near the front end thereof, two pulleys made stationary at the top of the bail and one at the rear of the scoop and made stationary therewith, a chain linked at the front end of the scoop and to the sides thereof with a pulley at the center, to which pulley is linked a cable adapted to draw the scoop forward and another cable passing from thence over one of the pulleys at the top of the bail, thence back over the pulley at the center of the chain, thence over the other pulley at the top of the bail, thence under the pulley made stationary to the back end of the scoop, thence over a pulley to the rear of the scoop and adapted to draw the scoop backward, substantially as set forth.

2. In an apparatus for excavating, dredging and transporting earth and other materials, the combination of a scoop having closed back, bottom and sides and open front and top, with strengthening plates secured to the sides and bottom thereof and extending a distance forward beyond the scoop, the ones on the sides adapted to engage the earth when the scoop is tilted forward in loading and to prevent the scoop from tipping side-wise, and the ones on the bottom inclined upward from the horizontal as they extend forward for a distance from the front and beveled at the front ends thereof and adapted for cutting engagement with the earth when the scoop is tilted forward and to release the scoop from cutting engagement with the earth when the same is in a horizontal position, with two cables operating over pulleys attached to the scoop, one of which cables is adapted to draw the scoop forward and the other to draw the scoop backward, substantially as set forth.

In testimony whereof, I have signed my name to this specification in the presence of two subscribing witnesses.

WILLIAM C. WEEKS.
